UNITED STATES PATENT OFFICE.

CHRISTIAN E. CALLAHAN, OF WILLARD, OHIO, ASSIGNOR TO THE PIONEER RUBBER COMPANY, OF WILLARD, OHIO, A CORPORATION OF OHIO.

ASSEMBLY DISK FOR ELASTIC MATERIAL.

Application filed June 25, 1927. Serial No. 201,306.

My invention has for its object to provide a connector for one or more elastic members. The invention particularly has for its object to provide a means for securing rubber to 5 an object.

The invention may be used in connection with a great variety of devices where elastic rubber parts are to be connected. The invention consequently may be contained in structures 10 of different forms and to illustrate a practical application of the invention, I have selected a device having two rubber parts that are to be interconnected. The construction selected is a "come-back" balloon, and 15 illustrates the different embodiments of my invention. The "come-back" balloon referred to is shown in the accompanying drawing and is described hereinafter.

Fig. 1 is a perspective view of the connector member greatly enlarged. Fig. 2 illustrates a top view of the connector showing the rubber string connected to the connector and in position for the connection of the rubber stem or neck of the balloon. Fig. 3 is a 25 view similar to that shown in Fig. 2 after the balloon has been inflated and the neck has been twisted and illustrates the manner in which the balloon is secured to the string. Fig. 4 is a side view of the balloon and the 30 string and an edge view of the connector.

In the form of construction shown in the drawing, the connector consists of a sheet material of relatively considerable stiffness, preferably cut in the form of a disk or washer. The disk is preferably punched from 35 sheet fiber, and in punching, a central opening is formed and cuts are produced in the outer and inner edges of the disk in which the rubber elements that form the toy are 40 secured.

The disk or washer 1 has a central opening 2. It is provided with a plurality of short cuts or slots 3. The cuts may be suitably located in the edges of the disk and so that 45 when the elastic string 4 is drawn in the cuts 3, it will be pinched by the edges of the cuts. In order that the body of the string may extend substantially from the center of the disk, a cut is made in the central edge portion thereof, such as the cut 5. Thus the 50 rubber string 4 may be secured to the disk by being forced into one of the cuts 3 that is formed in the peripheral edge of the disk and drawn to the cut 5 that is formed in a central portion of the disk. In order to

doubly secure the elastic string to the connector, it is secured in one of the cuts 3 and is then drawn over the disk and inserted in the other of the cuts 3 in the peripheral edge of the disk and then through the central 60 opening 2 and then drawn into the cut 5. This securely connects the elastic string and eliminates unsatisfactory tying of the rubber string which invariably causes tearing of the rubber unless the knotting is so loose 65 that it invariably comes untied. The edges of the cuts operate to merely tightly pinch the rubber at a plurality of points and thus securely connects the elastic string to the connector or to any object to which the connector may be secured. 70

The particular connector shown in the drawing is also so constructed that it may be connected to a toy balloon. In making the connection with the toy balloon, the neck of 75 the bladder is inserted through the opening 2. The balloon is then inflated and the neck of the balloon is secured to the connector in substantially the same manner that the string is connected to the connector. 80

In order to connect the balloon to the connector, the disk 1 is provided with a plurality of cuts in its edges into which the stem of the balloon may be drawn so that the stem will be pinched by the opposed edges 85 of the cuts. In the particular construction shown, the outer, or peripheral, edge of the disk 1 is provided with the cuts 6 which are, preferably, deeper, that is, longer, than the cuts 3 and 5. They are thus formed 90 owing to the quantity of rubber that is located in the neck of the balloon as compared with the cross dimensions of the rubber string. The width of the slots or cuts 6 that are thus formed may also be slightly 95 greater than the width of the slots or cuts 3 and 5 for the same reason. When it is desired to connect the connector 1 with the balloon, the neck is inserted through the opening 2 and after it is inflated it may be 100 slightly twisted. The neck is then drawn through one of the cuts 6 and across to the other cut 6. The arrangement is such that the string 4 protrudes from one side of the disk, which may be referred to as the top 105 side of the disk. The stem of the balloon is drawn to one of the cuts 6, and to the opposite side of the balloon and then upwards to the top side and into the other cut 6. When the stem has been slightly twisted to 110

close and prevent the escape of the air that is used to inflate the balloon, and the stem is secured in the cuts, untwisting of the stem will be prevented and thus the balloon will be maintained in its closed and inflated condition.

In making the connection between the balloon and the rubber string, preferably, an end portion of the string 4 is inserted 10 through the opening 2 and drawn into the cut 5, thence along the under side of the disk 1 to one of the cuts 3, and thence across the top of the disk to the other cut 3. Preferably, the cuts 3 are located in a line that 15 forms a chord of the outer edge of the washer that is located outside of the circle of the washer and also preferably the cuts 6 are located diametrically opposite to each other which positions the portion of the stem located on the under side of the disk 1 in 20 close contact with the balloon, it being drawn into the opening 2 by the elasticity of that portion of the neck located on the upper side of the disk 1. This locates the base of 25 the neck of the balloon substantially in line with the body of the string 4 where it terminates in the cut 5, it being crowded over to this position by that portion of the neck of the balloon located on the under side of 30 the disk. Thus the balloon and the rubber string will be securely connected together without knotting or tying and without tearing the rubber of the string or the rubber of the balloon which gives a long life to the 35 toy.

I claim:

1. In a connector for an elastic member, a 40 relatively stiff sheet material part having an opening formed therein and having slots extending from the inner and outer edges of the sheet material part, the edges of the slots being positioned sufficiently close to pinch the elastic member between the edges of the slots when the elastic member is forced into the 45 slots.

2. In a connector for a pair of elastic members, a relatively stiff sheet material part having an opening, slots extending from the inner and outer edges of the sheet material part, the edges of the slots being positioned sufficiently close to pinch the elastic members between the edges of the slots when the elastic members are forced into the slots, the body portions of the said elastic members 55 extending from the said opening in the sheet material part.

3. In a connector for a string of elastic rubber, a washer having a plurality of slots extending from its inner and outer edges, 60 the edges of the slot being positioned sufficiently close to pinch the elastic string between the edges of the slots when the elastic string is forced into the slots, the end portion of the elastic string extending from and 65 secured in a slot located in the outer edge

portion of the washer and to and secured in a second slot in the outer edge portion of the washer and to and secured in a slot in the inner edge portion of the washer.

4. In a "come-back" balloon having a string 70 of elastic rubber, a washer having a plurality of slots extending from its inner and outer edges, the edges of the slots being positioned sufficiently close to pinch the elastic material 75 between the edges of the slots when the elastic material is forced into the slots, the end portion of the elastic string extending from and secured in a slot located in the outer edge portion of the washer and to and secured in a slot in the inner edge portion of the washer, the neck of the balloon extending from and located in the opening in the washer and to and secured in a slot in the outer edge portion of the washer and extending to and secured in a second slot in the outer edge portion of the washer. 80

5. In a toy balloon, a washer having a plurality of slots located in its outer edge, the edges of the slots being positioned sufficiently close to pinch the neck of the balloon 90 between the edges of the slots when forced into the slots, the neck of the balloon extending through the opening of the washer and to and secured in one of the slots and extending across the washer and to and secured in another of the slots. 95

6. In a "come-back" balloon having a string of elastic rubber, a washer having a plurality of slots extending from its inner and outer edges, the edges of the slots being positioned sufficiently close to pinch the elastic material 100 between the edges of the slot when the elastic material is forced into the slots, the end portion of the elastic string extending from and secured in a slot located in the outer edge portion of the washer and to and secured in a second slot in the outer edge portion of the washer and to and secured in a slot in the inner edge portion of the washer, the neck of the balloon extending from and located in the opening in the washer and to and secured in a slot in the outer edge portion of the washer and extending to and secured in a second slot in the outer edge portion of the washer, the last 105 named second slot being located diametrically opposite the first named slot in which the neck of the balloon is secured. 110

7. In a "come-back" balloon having a string of elastic rubber, a washer having a plurality of slots extending from its inner and outer edges, the edges of the slots being positioned sufficiently close to pinch the elastic material 120 between the edges of the slot when the elastic material is forced into the slots, the end portion of the elastic string extending from and secured in a slot located in the outer edge portion of the washer and to and secured in a second slot in the outer edge portion of the washer and to and secured in a slot in the inner edge portion of the washer, the neck of the balloon extending from and located in the opening in the washer and to and secured in a slot in the outer edge portion of the washer and extending to and secured in a second slot in the outer edge portion of the washer. 125

ctured in a slot in the inner edge portion of the washer, the neck of the balloon extending from and located in the opening in the washer and to and secured in a slot in the outer edge portion of the washer and extending to and secured in a second slot in the outer edge portion of the washer, the last named second slot being located diametrically opposite the first named slot in which the neck of the

balloon is secured, the first named two slots 10 in which the elastic string is secured in being located in a line that forms a chord of the outer edge of the washer and which is located outside of the circle of the opening in the washer. 15

In witness whereof I have hereunto signed my name to this specification.

CHRISTIAN E. CALLAHAN.
